UNITED STATES PATENT OFFICE.

JOHN TREBER, OF CYNTHIANA, OHIO.

WINE AND CIDER PRESS.

SPECIFICATION forming part of Letters Patent No. 271,161, dated January 23, 1883.

Application filed August 28, 1882. (No model.)

To all whom it may concern:

Be it known that I, JOHN TREBER, a citizen of the United States of America, residing at Cynthiana, in the county of Pike and State 5 of Ohio, have invented certain new and useful Improvements in Wine and Cider Presses; and I do declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 This invention relates to certain new and useful improvements in wine and cider presses; and it consists in the novel construction and combination of the parts, as will be hereinafter set forth, and pointed out in the claims.

20 On the annexed drawings, Figure I is a top or plan view. Fig. II is a longitudinal section through the line *x x*. Fig. III is a transverse section through the line *y y*.

A represents the frame, which is provided 25 with transverse beams suitably located and provided with shaft bearings and supports for elevating the same, so that receptacles can be placed under the apparatus for the reception of the juice and pomace.

30 Cross-bars B B are attached to the frame, and serve to hold the longitudinal bars of the frame together. These transverse bars, except those at the end of the frame, are elevated and provided with shaft-bearings, which hold 35 the shafts, to be hereinafter described, in an inclined position.

The shafts C and C' are secured to the frame so as to be capable of a slight longitudinal adjustment, which is accomplished by providing 40 the shafts at their ends with depressions, in which fit screw-threaded adjusting-bolts *a*, which bolts pass through the end cross-bars at an angle so as to be on the same line with the inclined shaft, the adjusting-bolts forming 45 the end bearing of the shafts C and C'. These shafts on the other end are provided with a ball-and-socket, or similar universal joint. The socket portion of this connection is oblong in shape, and the end of the opposite shaft is cut 50 away before reaching the ball, so as to pro-

vide a neck of reduced size. By this means the shaft which carries the crushing-disks can be adjusted longitudinally, and the ball-and-socket joint will form a central bearing.

Attached to the shafts C and C' are crushing devices, which consist of two disks, D and D', having inclined faces and central portion at right angles with the shafts. These crushing-disks are provided on their inner faces with suitable gear-teeth, which mesh into each other 55 and cause the same to rotate equally. These disks, being arranged upon the shafts and constructed as described, meet so as to form parallel crushing-surfaces at a point below the frame.

The crushing disk B' near its rim is provided with gear-teeth E, into which the driving-wheel F meshes. This driving-wheel is supported upon a frame by a suitable raised cross-bar having an upright bearing, upon which 70 the driving-wheel rotates. The driving-wheel is provided at the upper end of its extending socket, as shown, with a sweep or lever for operating the parts. By means of this sweep and connecting means the disks are rotated so 75 the upper part of the same will turn toward the hopper, as will be hereinafter set forth.

Attached to the frame A, opposite the disks, and extending downwardly near the meeting points of the same, is a guide, G, which prevents the fruit falling out between the rollers while it is being carried toward the crushing portion and above the frame. Over this guide G is attached a hopper, H, having inclined sides and bottom, the bottom being provided 80 with an adjustable guide, I, which is secured to the hopper by a set-screw. To the opposite side of the frame, so as to extend between the rotating disks, is a scraper, J, which tapers from the portion attached to the frame, which 85 end is bent downward, as shown in Fig. III. Above the scraper J, and secured to the frame by the same connecting means, is a curved cover or hood, K, which is tapered, as shown in Fig. I. This curved hood K prevents the 90 fruit which is placed in the hopper coming in contact with the gears on the disks, and forms, with the guide I, a throat or passage-way for the fruit.

The operation of this invention may be de- 100

scribed as follows: For pressing apples to make cider, the apples are placed in the hopper, the slide being adjusted so as to leave an opening which will correspond relatively to the size of the apple and to the speed at which the crushing-disks are rotated. The rollers, being turned toward the hopper, draw the apples downwardly toward the parallel abutting portion of the disks, between which the juice is expressed from the fruit, which flows into a suitable receptacle placed under the frame. The pomace is carried upward by the disks, and is removed therefrom by the scrapers and falls into a receptacle separated from the juice.

Having thus described my invention, what I claim as new, and desire to secure by Letters Patent, is—

1. In combination with a pair of disks having inclined crushing-surfaces, mounted on inclined shafts, connected to each other at their ends, the whole being mounted on a frame and provided with rotating means, substantially as described.

2. In a cider or wine press, the inclined disks arranged so as to provide parallel crushing-surfaces at their lower portion, substantially as described. 25

3. In a wine or cider press, the combination, with the inclined crushing-disks, of a curved hood, hopper, with adjustable slide, and scraper, 30 arranged and organized substantially as shown, and for the purpose set forth.

4. In a wine and cider press, the inclined crushing-disks provided with gear-wheels on their inner faces, and mounted upon inclined 35 shafts, with end-bearing means, in combination with a curved hood, hopper, with adjustable slide, and scraper, the parts being arranged and operated substantially as shown, and for the purpose set forth. 40

In testimony whereof I affix my signature in presence of two witnesses.

JOHN TREBER.
